CLAIM

The ornamental design for a notebook computer as shown and described.

DESCRIPTION

FIG. 1 is a perspective view of a notebook computer showing our new design in an opened state of use; FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the portion, labeled '9' of FIG. 7;

FIG. 10 is another perspective view thereof of the notebook computer of FIGS. 1-10 showing the notebook computer in a closed state; and,

FIG. 11 is another perspective view thereof of the notebook computer of FIGS. 1-10 showing the notebook computer in the closed state.

The even-dashed broken lines shown in the drawings illustrate portions of the notebook computer that form no part of the claimed design. The dash-dot-dot broken lines in FIGS. 7 and 9 represent the extents of the enlarged detail view and form no part of the claimed design.
